(57) **CLAIM**

The ornamental design for a church picture frame, as shown and described.

DESCRIPTION

FIG. 1 is a front elevational view of the picture frame.

FIG. 2 is a rear elevational view of the picture frame.

FIG. 3 is a side elevational view of the picture frame with the opposite side being a mirror image.

FIG. 4 is a top plan view of the picture frame; and,

FIG. 5 is a bottom plan view of the picture frame.

The broken lines are for environmental purposes only and form no part of the claimed design.
